UNITED STATES PATENT OFFICE.

ANNA F. DESMOND, OF LOS ANGELES, CALIFORNIA.

DESIGN FOR AN INCENSE-BURNER.

56,342.

Specification for Design.

Patented Oct. 5, 1920.

Application filed November 10, 1919. Serial No. 337,020. Term of patent 7 years.

To all whom it may concern:

Be it known that I, ANNA F. DESMOND, feme sole, a citizen of the United States, residing at Los Angeles, in the county of Los Angeles and State of California, have invented a new, original, and ornamental Design for an Incense-Burner, of which the following is a specification, reference being had to the accompanying drawing, forming part thereof.

Fig. 2 is a perspective view of the same.

I claim:

The ornamental design for an incense burner, as shown.

ANNA F. DESMOND.

Witnesses:

EDMUND A. STRAUSE,
MAUDE A. WOOD.
